BEDSIDE COMMODE

Morton I. Thomas, Bakertown Road,
Monroe, N.Y. 10950

Filed June 4, 1973, Ser. No. 366,500

Term of patent 14 years

Int. Cl. D23—02

U.S. Cl. D23—48

FIG. 1

FIG. 2

FIG. 3

FIG. 1 is a perspective view of a bedside commode showing my new design, with the left arm in a raised position;

FIG. 2 is another perspective view thereof, showing the right arm in a raised position; and

FIG. 3 is a third perspective view thereof, showing both arms and the lid in raised position.

I claim:

The ornamental design for bedside commode, substantially as shown and described.
